DESIGN FOR A CAPE OR SIMILAR ARTICLE

Max Levitt, New York, N. Y.

Application December 15, 1941, Serial No. 104,642

Term of patent 3½ years

To all whom it may concern:

Be it known that I, Max Levitt, a citizen of the United States of America, residing at New York, in the county of New York and State of New York, have invented a new, original, and ornamental Design for a Cape or Similar Article, of which the following is a specification, reference being had to the accompanying drawing, constituting a part thereof.

Figure 6 is a fragmentary side elevational view taken similarly to Figure 5 but with the lower part of a side portion of the cape in a spread out position.

I claim:

The ornamental design for a cape or similar article, as shown.

MAX LEVITT.
